UNITED STATES PATENT OFFICE.

CHARLES RALPH TOWNSEND AND JOSEPH GEORGE SKINNER, OF BIRMINGHAM,
ENGLAND.

CLAMPING-DOG.

1,326,807.

Specification of Letters Patent.

Patented Dec. 30, 1919.

Application filed June 13, 1918. Serial No. 239,906.

To all whom it may concern:

Be it known that we, CHARLES RALPH TOWNSEND and JOSEPH GEORGE SKINNER, subjects of the King of Great Britain, residing at Caxton House, Great Charles street, in the city of Birmingham, county of Warwick, England, have invented certain new and useful Improvements in and Connected with Clamping-Dogs, of which

10 the following is a specification.

The invention provides the hereinafter described and claimed improvements in and connected with clamping dogs or devices used for many purposes but generally used 15 to hold work to beds, tables, and face plates of machines, obviating the necessity of setting and of using pack-up pieces.

Usually such a dog or device is a flat or irregular shaped rigid piece through a slot 20 in which a clamping bolt passes, and when using same it is invariably necessary to pack-up with loose pieces of different thicknesses. Such packing up is tedious, often very difficult, and always mechanically bad, as no 25 matter how carefully performed the chances are that the position of the work will shift on final screwing up of the clamping bolt, frequently necessitating resetting.

The dog or device according to the invention embodies a rigidly built piece having 30 three curved co-acting surfaces, two of which constitute feet for gripping, and the other of which provides an elevated bolt-pulling-up abutment disposed between said feet. 35 Looked at sidewise said dog or device is substantially arch shape, the feet of the arch being the gripping feet, aforesaid, and the elevated surface the crown of the arch, or part adjacent forming the pulling up abutment. The curvings of the three surfaces 40 extend sidewise of the dog or device said surfaces transversely being preferably without curvature. The curves of the feet provide convexity, but the curve of the abutment may be either convex or concave. One 45 foot may be longer than the other, but preferably the curves thereof are alike as to radii. The bolt may pass freely through a slot in the dog or device arranged between 50 the feet to engage either a washer contacting the abutment or a block or piece rocking on the abutment, said washer or piece providing a flat surface for the nut of the bolt to

pull up against and being shaped at its contacting face to the shape of the abutment. 55

The invention is represented by the accompanying drawing in which Figure 1 is a side elevation and Fig. 2 a plan of the device.

The dog or device is composed of rigidly 60 built pieces or sections e^2 and e^3 each provided with three curved co-acting surfaces f , g and h . Each dog or device section is substantially arch-shape sidewise and the surfaces f and g provide convex feet and the 65 surface h a convex crown or pulling up abutment for the bolt d . The curvings are sidewise only of the dog or device, said surfaces transversely having no curvature.

The curved surface h co-acting with the 70 curved surfaces f and g is provided by the lower halves of opposite transverse holes n and o , formed through the dog or device body between the feet to provide bearings for trunnions n^2 o^2 , of a rocking block, i , 75 working in the slot l and through a hole i^4 , in which a pulling up bolt is adapted to pass. This dog is built up of three pieces, the one the pivoted block i and the others the two halves e^2 e^3 of the dog or device 80 body, which halves are put together at machined facings, e^4 , and riveted up, at e^5 e^6 , with the block between them so that the latter is always a permanent part of the dog or device. 85

The co-acting curved surfaces f , g and h are true ones, preferably machined or ground so as not to have any irregularities, same being transversely parallel with each other. Said surfaces may be slightly 90 roughened or matted.

A dog or device according to the invention in addition to being self setting, and pulling up true in all conditions within its range of thickness grip is free from slip, so 95 that once the work is adjusted by a partial pulling up the final screwing up of the bolt will not cause any shifting. Further said dog or device has no set positions being infinitely variable within its range of thickness-grip and has no adjustment requiring skill. 100

Having now described our invention what we claim and desire to secure by Letters Patent is:—

1. A clamping dog comprising a rigid 105 body structure having convex gripping feet,

and a block applied to said body structure between the feet and having trunnions engaging parts of the body structure and also provided with a hole therethrough for the reception of a bolt.

- 5 2. A clamping dog comprising a rigid body structure having convex gripping feet, and a block applied to said body structure between the feet and having trunnions engaging parts of the body structure to provide a rocking movement for the block, the block being retained in association as a part of the dog and having an opening therethrough for the reception of a bolt.
- 10 10 3. A clamping dog comprising a rigid body structure having convex gripping feet

composed of half sections formed with opposite bearing holes, and a block applied to the body structure between the feet and having trunnions engaging said bearing holes to set up a rocking action of the block, the block being formed with an opening therethrough for the reception of a bolt.

20 In testimony whereof we have hereunto set our hands in presence of two subscribing 25 witnesses.

CHARLES RALPH TOWNSEND.
JOSEPH GEORGE SKINNER.
